United States Patent Office

Des. 218,957

Patented Oct. 20, 1970

218,957

SHOULDER WARMER

Maurice Pichon, Saint Etienne, France, assignor to Pichon Freres Societe Anonyme, Saint Etienne, Loire, France, a corporation of France

Filed July 30, 1969, Ser. No. 18,477

Term of patent 7 years

Int. Cl. D2—01

U.S. Cl. D2—192

FIG. 1

FIG. 2

FIG. 1 is a front elevational view of a shoulder warmer showing my new design; and

FIG. 2 is a rear elevational view thereof.

I claim:

The ornamental design for a shoulder warmer, as shown.
